Term of patent 14 years

(Cl. D26—5)

Fig. 1

Fig. 2

Fig. 3

FIGURE 1 is a front, top and right side perspective view of a modular electronic cabinet, showing my new design;

FIGURE 2 is a rear, top and left side perspective view; and

FIGURE 3 is a fragmentary perspective view thereof, to an enlarged scale, taken on lines 3—3 in FIG. 1.

The essential features of my design reside in the portions shown in solid lines.

I claim:

The ornamental design for a modular electronic cabinet, as shown and described.
